[57] **CLAIM**

The ornamental design for a combined toy tubular beam and blocks, as shown and described.

DESCRIPTION

FIG. 1 is a front elevational view of a combined toy tubular beam and blocks showing my new design, the rear elevational view being identical;

FIG. 2 is a left side elevational view thereof, the right side elevational view being identical;

FIG. 3 is a top view thereof;

FIG. 4 is a bottom view thereof;

FIG. 5 is a cross-sectional view of the block of combined toy tubular beam and blocks; and,

FIG. 6 is a cross-sectional view of the circular beam of combined toy tubular beam and blocks.
